AMUSEMENT APPARATUS EMBODYING A PUPPET

Harry E. Williams, Pacific Palisades, Calif., assignor to
Harry Williams Manufacturing Company, Chicago, Ill.,
a corporation of Illinois

Application July 25, 1956, Serial No. 42,391

Term of patent 3½ years

(Cl. D34—5)

Fig. 1 is a perspective view of an amusement apparatus embodying a puppet, showing my new design; and
Fig. 2 is a side elevational view thereof.

The drawings are diagonally lined to indicate that portion of the apparatus which is transparent.

I claim:

The ornamental design for an amusement apparatus embodying a puppet, as shown and described.
